UNITED STATES PATENT OFFICE.

JOHN A. WILSON, JR., OF BUFFALO, NEW YORK, ASSIGNOR TO NOYE MANUFACTURING COMPANY, OF BUFFALO, NEW YORK, A CORPORATION OF NEW YORK.

RADIATOR.

982,334.

Specification of Letters Patent. Patented Jan. 24, 1911.

Application filed April 23, 1909. Serial No. 491,672.

To all whom it may concern:

Be it known that I, JOHN A. WILSON, Jr., a citizen of the United States, and residing at Buffalo, in the county of Erie and State 5 of New York, have invented a new and useful Improvement in Radiators, of which the following is a specification.

This invention relates to that class of automobile radiators in which the water to be cooled is circulated through a plurality of vertical tubes through which the water passes downwardly.

In this class of radiators, as heretofore constructed, the hot water has usually been admitted to the upper ends of the tubes and the cooled water withdrawn from the lower ends thereof, the water being kept in circulation in the radiator and the jacket of the engine with which it is connected by thermal action in a well known manner. In these prior radiators the head of the water was comparatively low which necessitated heating the water to an unduly high temperature in order to cause it to circulate sufficiently fast which excessive heating maintains the radiator at an objectionably high temperature and also causes the water to evaporate too rapidly, necessitating too frequent replenishing of the water supply in order to prevent the level of the same from dropping below the inlet at the top of the radiator which is commonly known as "loosing the water."

The object of this invention is to provide a radiator which has a head of water of greater height above the inlet so that the water is caused to circulate with sufficient rapidity without excessive heating of the same, thereby keeping the radiator cooler and avoiding undue evaporation of the water and necessitating less frequent replenishing of the same.

In the accompanying drawings Figure 1 is a front elevation, partly in section, of one form of my improved radiator. Fig. 2 is a vertical section of the same.

Similar letters of reference indicate corresponding parts in both views.

A represents a plurality of upright upper tubes which are preferably arranged in transverse and longitudinal rows and B represents a plurality of upright lower tubes which are similarly arranged. The upper ends of the upper tubes open into the underside of an upper tank or manifold C

which serves to connect the upper ends of the passages in these tubes. At the lower ends of the lower tubes is arranged a lower tank or manifold D into the upper side of which the lower ends of the lower tubes open and which serves to connect the lower ends of the passages in these tubes. On its rear side the lower tank is provided with one or more water outlet nipples 'd' which connect with the return pipes of the water circulating system leading to the water jacket of the engine, two of such outlet nipples being preferably employed, as shown in Fig. 1.

Between the upper and lower sets of tubes is arranged an intermediate or central tank or manifold E which contains one or more diaphragms or partitions F, two being preferably employed, near opposite ends of the same, as shown in Fig. 1. These partitions divide the interior of the central manifold into a main transfer chamber g which is wide at the bottom and connected centrally at the top, and two inlet chambers f at opposite ends of the central manifold. Each of the inlet chambers is provided on its rear side with a water inlet nipple e which is adapted to connect with a supply pipe of the water circulating system leading from the water jacket of the engine.

The upper ends of the lower tubes open through the bottom of the central manifold and into the wide lower part of the transfer chamber therein and the lower ends of the central group of upper tubes open at their lower ends through the top of the central manifold into the upper contracted part of the transfer chamber.

The side groups of upper tubes open at their lower ends through the top of the central manifold, each group communicating with the inlet chamber f at the corresponding end of the central chamber.

The hot water from the engine entering through the inlet nipples first passes into the inlet chambers, thence upwardly through the side groups of upper tubes, thence through the upper manifold, thence downwardly through the central group of upper tubes, thence into the transfer chamber of the central manifold, thence downwardly through the lower tubes, thence into the lower manifold and thence out through the lower nipples and into the return pipes leading to the water jacket of the engine.

As the water passes through the tubes the same is cooled by the air passing between the tubes, this cooling effect being preferably increased by providing the tubes with radiating strips h which are partially corrugated and are penetrated by the tubes in the usual and well known manner.

By arranging the water inlet or supply for the tubes at a point between the upper and lower ends of this system of cooling tubes, a greater head of water is maintained in the radiator above the water inlet the pressure of which causes the water to circulate more rapidly without heating the water to as high a temperature as has been necessary heretofore, thereby keeping the radiator cooler and reducing the evaporation of water which in turn lengthens the intervals of time for effecting refilling of the radiator with water to compensate for the evaporation. The increased head of water in this radiator is obtained without sacrificing any tube area, so that the radiating surface is practically the same with the advantage of more rapid circulation, less heating of the water and retaining the radiator in cooler condition.

I claim as my invention:

1. A radiator comprising a plurality of upper upright tubes, a plurality of lower upright tubes, a connection between the upper ends of said upper tubes, means connecting the lower ends of some of said upper tubes and provided with a water inlet, means connecting the lower ends of the other upper tubes with the upper ends of said lower

tubes, and means connecting the lower ends of the lower tubes and provided with a water outlet.

2. A radiator comprising a plurality of lower upright tubes, a plurality of upper upright tubes, an upper tank or manifold connected with the upper ends of the upper tubes, a lower tank connected with the lower ends of the lower tubes and provided with a water outlet, an intermediate tank connected with the upper ends of the lower tubes and the lower ends of some of the upper tubes, and an auxiliary tank or manifold connected with the lower ends of other upper tubes and provided with a water inlet.

3. A radiator comprising a plurality of lower upright tubes, a plurality of upper upright tubes, an upper tank or manifold connected with the upper ends of the upper tubes, a lower tank connected with the lower ends of the lower tubes and provided with a water outlet, an intermediate tank connected with the upper ends of the lower tubes and the lower ends of some of the upper tubes, and an auxiliary tank or manifold arranged within the intermediate tank or manifold and connected with the lower ends of other upper tubes and provided with a water inlet.

Witness my hand this 20th day of April, 1909.

JOHN A. WILSON, JR.
